UNITED STATES PATENT OFFICE.

THOMAS R. KENNEDY AND EDWARD J. KING, OF ROCHESTER, NEW YORK, ASSIGNEES
TO COOPERATIVE FOUNDRY COMPANY, OF ROCHESTER, NEW YORK, A CORPORATION
OF NEW YORK.

DESIGN FOR A STOVE.

40,614.

Specification for Design.

Patented Apr. 5, 1910.

Application filed April 12, 1909. Serial No. 489,536. Term of patent 7 years.

To all whom it may concern:

Be it known that we, THOMAS R. KENNEDY and EDWARD J. KING, citizens of the United States, residing at Rochester, in the county of Monroe and State of New York, have invented a new, original, and ornamental Design for Stoves, of which the accompanying drawing is a representation.

The figure is a perspective view of a stove, showing our new design.

We claim:

The ornamental design for a stove as herein shown.

THOMAS R. KENNEDY.
EDWARD J. KING.
